AIR CLEANER FOR ENGINES OR THE LIKE

Donald F. Haskin, 11416 Miranda St., North Hollywood,
Calif. 91601, and Max Becker, 14058 Valley Heart
Drive, Apt. 3, Sherman Oaks, Calif. 91403

Filed Apr. 22, 1968, Ser. No. 11,548

Term of patent 14 years

Int. Cl. D15—01

U.S. Cl. D23—149

FIG. - 1

FIG. - 2

FIG. - 3

FIG. 1 is a top view of our new air cleaner for engines or the like, design;

FIG. 2 is a side elevation view thereof; and

FIG. 3 is a bottom view thereof.

The dominant features of our design reside in the portion shown in full lines only.

We claim:

The ornamental design for an air cleaner for engines or the like, substantially as shown and described.
